Patented July 30, 1968

211,798

GAMEBOARD

Paul A. Dillingham, R.R. 1, East Hampton, Conn. 06424

Filed Sept. 1, 1967, Ser. No. 8,475

Term of patent 14 years

(Cl. D34—5)

The figure shows a plan view of a gameboard of conventional thickness embodying my novel design the conventional legible matter being shown in broken lines.

I claim:

The ornamental design for a gameboard, as shown and described.
